UNITED STATES PATENT OFFICE.

BENJAMIN F. SLOAN, OF LEXINGTON, KENTUCKY, ASSIGNOR OF ONE-HALF
TO CHARLES W. BRADLEY, OF SAME PLACE.

TRICYCLE.

SPECIFICATION forming part of Letters Patent No. 261,395, dated July 18, 1882.

Application filed December 31, 1881. (No model.)

To all whom it may concern:

Be it known that I, BENJAMIN F. SLOAN, of Lexington, in the county of Fayette and State of Kentucky, have invented a new and Improved Tricycle, of which the following is a full, clear, and exact description.

The object of my invention is to provide a new and improved tricycle which can be propelled easily, and the speed of which can be varied conveniently, as the circumstances may require.

Reference is to be had to the accompanying drawings, forming part of this specification, in which similar letters of reference indicate corresponding parts in all the figures.

Figure 1 is a longitudinal elevation of my improved tricycle. Fig. 2 is a plan view of the same. Fig. 3 is a detail cross-sectional elevation through the middle part of the wheel.

The driving-wheel A is loosely mounted on the axle or shaft B, which is journaled in the fork C, swiveled to the curved reach D, formed of two spreading-bars, D', bent angularly at their lower ends and united by a platform, C', for carrying a seat, C². The lower or rear ends of the reach-bars D' rest on an axle, E, journaled in the rear wheels, E', which axle is fastened rigidly to the ends of these reach-bars. To protect the person or persons occupying the seat C² from the mud or sand thrown up by the wheel A, the bars D' D' are united by a covering, D², of metal, leather, &c. The spring-seat F rests on the upper part of the reach D and is fastened thereon in the ordinary manner. A treadle-bar, G, is loosely mounted on each end of the shaft B, and at one end carries an adjustable revolving foot-rest, F', and has a quadrant or segmental part, F², attached to its other end, the arm G' connecting the outer end of this quadrant with the middle of the treadle-bar. A rod, H, is hooked on the quadrant F², which rod passes through a guide-loop, H', on the curved reach D, to the seat C², and is provided with a handle-loop, H². A rod, I, is hooked into that end of the treadle-bar G opposite the one to which the foot-rest F' is fastened, is guided by an arm, e, of the fork C, and is provided with a handle-loop, I', at its upper end, this rod I being of such length that it can be grasped easily by the person occupying the seat F. A ratchet-wheel, J, which

is made integral with a pinion, K, is rigidly mounted on the shaft B, between the treadle-bar G and the right-hand shank of the fork C. One or more spring-pawl, L, pivoted to the 55 arm G', rest on the periphery of the ratchet-wheel J.

Between the hub Q of the wheel A and the right-hand shank of the fork C a disk or wheel, M, or a suitable arm is rigidly mounted on the 60 shaft B, and to this disk or arm one or more pawls, N, are pivoted, which rest on a ratchet-wheel, O, made integral with a cog-wheel, P, attached to the hub Q of the driving-wheel A, the combined ratchet and cog wheel O P being also loosely mounted on the shaft B in the same manner as the wheel A is.

A shaft, R, is journaled in the lower end of a lever, S', and in a block, R', grooved on the under side, so as to fit closely and be adapted 70 to slide on the upper edge of the arm S. On this shaft R are mounted a cog-wheel, T, adapted to engage with the pinion K on the shaft B, and a pinion, T', adapted to engage with the cog-wheel P, attached to the hub Q of the wheel A. The lever S' is pivoted to a projection, d, of the lower end of the fork C, and is guided by an arm, e, of this fork. This lever S' is of such length that it can be operated easily by the person occupying the seat F. 80

Between the hub Q of the wheel A and the left-hand shank of the fork C a disk or wheel, M', or a suitable arm is rigidly mounted on the shaft B, and to this disk or arm one or more pawls, N', are pivoted, which pawls 85 rest on a ratchet-wheel, O', made integral with a pinion, P', attached to the left-hand end of the hub Q, which combined pinion and ratchet-wheel O'P' are loosely mounted on the shaft B.

In the sliding block R' on the left-hand arm, 90 S, there is a shaft, R, also journaled in the lower end of a lever, S', on the left-hand side of the fork, and on this shaft R are mounted a cog-wheel, T², engaging with the pinions P' on the hub Q, and a pinion, T³, engaging with a cog-wheel, K', rigidly mounted on the shaft. The arm S of the fork C is provided with a curved brace, U, which is rigidly attached to the top of the fork C. The arm S is so constructed that a wheel, V, journaled in the front 100 forked end of this arm S will not touch the ground, but will be a short distance above it.

The steering-lever W is pivoted to the upper end of the fork C, and is provided with a quadrant-plate, X, fitting in between two projections, Y, of the upper end of the curved reach D. The brake-shoe Z is pivoted to the under side of the brace U. The outer end of this brake-shoe Z is provided with an upwardly-projecting block, Z', passing through an opening or slot in the curved brace U, and having 10 a grooved pulley, Z², provided in its upper end. A cord, U², passes over this pulley and is attached to each treadle-bar G. The block Z' is provided with a transverse aperture, adapted to receive a wedge-shaped projection, m, of 15 a lever, n, pivoted to a lateral projection of the curved brace U. If the lever n is pushed from the seat, the wedge-shaped projection m will raise the block Z' and the brake-shoe Z and prevent the brake from being pressed on 20 the wheel, the cord U² passing over the pulley Z' in opposite directions alternately as the treadle-bars are alternately depressed.

To use the brake, the lever n is pulled back and the projection m is withdrawn from the aperture in the block Z'. The brake-shoe can now 25 be lowered, and by putting an equal stress on each treadle the entire weight of the body can be brought on the brake. The cord U² will pass down behind the levers S' S', and will 30 not interfere with them.

A longitudinally-slotted segmental guide-bar, D³, is fastened under the lower parts of the bars D' D', which guide D³ projects a slight distance sidewise beyond each bar D'. A V-shaped rod or frame, C³, or any other like suitable frame, is pivoted or hooked to the lower ends of the shanks of the fork C. The other or outer end of the frame passes through the guide-slot in bar D³, and is secured by a pin 35 passing through two rollers, m', adapted to roll on the outer surface of the guide-bar D³. This frame C³ draws the weight of the rear seat and wheels, thereby greatly relieving the reach-bars D'. The fork C is to be so arranged as to 40 be inclined backward two or three inches, in order to avoid the danger of upsetting the tricycle.

The tricycle can be constructed with or without the rear seat and platform. It is evident 50 that the above-described construction is also applicable to a bicycle as well as a tricycle.

The operation is as follows: The rider occupies seat F and propels the vehicle by depressing the treadle-bars G, thereby causing the 55 pawls L to act on the ratchet-wheels J, whereby the shaft B is rotated in the direction of the arrow a'. The wheel M is rotated in the same direction, and the pawl N, engaging with the ratchet-wheel O, rotates the driving-wheel A 60 in the direction of the arrow a'. If the resistance is very great, the rider can add to the driving-power by pulling upward on the rod I, and the person or persons occupying the seat C² can assist by pulling on the rods H. A reciprocating movement of the treadle is preferable; but if the rods H and I are detached a 65 rotary motion can be given to the treadle, each

foot making an entire revolution for each revolution of the shaft. If great speed is desired, the left-hand lever S' is pushed in the direction of the arrow b', thereby engaging the pinion T³ with the cog-wheel K' and the cog-wheel T² with the pinion P', the block R' sliding up the arm S. The cog-wheel K' will rotate the pinion T³, which is much smaller, thereby causing the left-hand shaft, R, to be rotated very rapidly. The wheel T² will also revolve very rapidly and cause a still more rapid revolution of the pinion P' and the wheel A—that is, the wheel A will rotate much more rapidly than the shaft B, and the pawls N' N' will slide over the teeth of the cog-wheel O, or they are previously raised. As soon as the rapid movement is to cease the pinion T³ and cog-wheel T² are disengaged from the cog-wheels K' and 70 pinion P' by pulling the left-hand lever S' in the inverse direction of the arrow b', causing the block R' to slide down the arm S. If an incline is to be ascended, the wheel A is caused to rotate much slower than the shaft 75 B by engaging the cog-wheel and pinion of the right-hand sliding block R' with the pinion K and cog-wheel P' on the right-hand end of the shaft. If the vehicle is to run along on a straight line, the steering-lever W is turned 80 down, as shown in Fig. 1, the circular projecting plate X passing in between the projections Y of the curved reach D, thereby locking the reach D and the front brace, U, in one straight line. If the vehicle is to be steered to one side, 85 the steering-lever W is raised and turned as may be necessary. If the brake is applied suddenly, the vehicle is apt to tip over toward the front. To prevent this I have provided the safety-wheel, which does not run on the ground, 90 but is a few inches above it, and only comes in contact with the ground when the vehicle tips toward the front.

Having thus fully described my invention, what I claim as new, and desire to secure by 95 Letters Patent, is—

1. The combination of the fork C, having arm S, the above-ground wheel V, journaled in the front forked end of said arm, a steering-lever pivoted at the upper end of said fork and 100 having a quadrant-plate, X, and the reach D, having projections Y Y, as shown and described.

2. The combination of the fork C, having a curved slotted top brace, U, with a lateral projection, the brake-shoe Z, pivoted to the under side of said brace, having transversely-apertured block Z', and provided with grooved pulley Z², the cord U², passing over said pulley and attached to each treadle-bar, and the lever 105 n, having wedge-shaped projection m, as and for the purpose set forth.

3. The combination, with the bars D' D', of the longitudinally-slotted segmental guide-bar D³, arranged below and projecting laterally beyond said bars, and the fork C, having pivoted thereto a frame, C³, secured by pin passing through rollers m', whereby the strain is taken 110 off the reach-bars D', as described.

4. The combination, with the seat F, of the treadle-bars G, pawls L, ratchet-wheels J, shaft B, wheel M, pawl N, ratchet-wheel O, and drive-wheel, all relatively arranged as shown and described. 50
5. The combination of the rods H, quadrant F², guide-loop H', and handle H², whereby the power may be augmented by the action of a person in the seat C², as described. 35
- 10 6. The combination of the rod I, having loop I', treadle-bar G, and the arm e on fork C, whereby the rider can add to the driving-power, as described. 40
7. The combination of the lever S', pinion T³, cog-wheels K' K², pinion P', and block R', adapted to slide up the arm S, whereby the speed may be increased, as set forth. 45
8. In a tricycle, the combination, with the shaft B, of the wheel A, loosely mounted thereon, the combined cog and spur wheel P O, made integral with the hub Q, the combined spur and cog wheel J K, rigidly mounted on the shaft, the pawl N of the disk M, the treadle-bars G, the pawl L, the pinion T, the cog-wheel T', the shaft R, the sliding blocks R', and the lever S', substantially as herein shown and described, and for the purpose set forth. 50
- 25 9. In a tricycle, the combination, with the shaft and wheels, of treadle-bars and cogs and pinions arranged in two sets at opposite sides of the fork, substantially as herein shown and described, and for the purpose of rotating the shaft and wheels faster or slower than the treadles, as may be desired. 50
10. In a bicycle or tricycle, the combination, with the treadle-bars G and the brake Z, of the cord U², substantially as herein shown and described, and for the purpose set forth. 35
11. In a tricycle or bicycle, the combination, with the brake Z, provided with the projection Z', of the cord U², the pulley Z², the treadle-bars G G, and the lever n, provided with a wedge-shaped projection, m, substantially as herein shown and described, and for the purpose set forth. 40
12. In a tricycle, the combination, with the curved reach-bars D', of the slotted segmental guide-bar D³, and the frame C³, pivoted to the bottom of the fork C and passing through the slot of the guide-bar D³, substantially as herein shown and described, and for the purpose set forth. 50
